UNITED STATES PATENT OFFICE.

THOMAS P. SULLIVAN, OF WEBSTER GROVES, AND EVAN McM. HAZARD,
OF ST. LOUIS, MISSOURI.

OIL-EXPRESSING BOX.

SPECIFICATION forming part of Letters Patent No. 320,896, dated June 23, 1885.

Application filed March 23, 1885. (No model.)

To all whom it may concern:

Be it known that we, THOMAS P. SULLIVAN and EVAN McM. HAZARD, residents, respectively, of Webster Groves, St. Louis county, Missouri, and the city of St. Louis, Missouri, have jointly made a new and useful Improvement in Oil-Expressing Boxes for Expressing Oil from Cotton-Seed and other Seeds, of which the following is a full, clear, and exact description.

The object of the improvement is to provide means for obviating the use of mats in oil-expressing boxes.

It consists, mainly, in the employment at the upper edges of the follower of a strip so constructed and attached that it shall, as the follower moves into the box, keep the joint between the follower and the box closed, and thereby prevent the bag which contains the seed from being caught and torn between the follower and the box.

The annexed drawings, making part of this specification, exhibit the most approved mode of carrying out the improvement.

Figure 1 is a plan of the box. Fig. 2 is a vertical cross-section on the line 2-2 of Fig. 1, the view showing two boxes as in use. Fig. 3 is a section on the line 3-3 of Fig. 1, and Fig. 4 is an edge elevation of one of the follower strips.

The same letters of reference denote the same parts.

The boxes A, saving as modified by the improvement, are of the customary form and used in the customary manner. B represents the strip for closing the joint between the follower C and the side of the box. These strips are preferably used only at the sides c c of the follower, the strips in practice not being needed at the ends of the follower.

In expressing the oil in the present instance the material from which the oil is obtained is put into a bag composed of a textile fabric—such as woolen cloth—and run through a former to impart an even thickness to the package. This package then, and without any outer mat or envelope, is placed within the box, resting upon the follower C of the box beneath.

Now, as a nest of oil-expressing boxes has heretofore been constructed there is a certain amount of play between the followers and the

boxes in which they respectively work. By reason of this loose fit the bag above named is liable to be caught between the sides of the follower and the inner side walls of the box, and to prevent this is the function of the strips B, which are so adjusted as to keep the joint closed as the follower and boxes move laterally upon each other. To this end the strip B is made laterally adjustable upon the follower, so that when the follower moves away from the side of the box the strip shall slip upon the follower and keep its outer edge, b, against the side a of the box, and when the follower sways in the opposite direction the strip shall, by reason of the side of the box pressing against the edge b, be slipped farther onto the follower, and thus in all positions of the follower act as a guard to close the entrance to the joint. To thus provide for an adjustable guard and to obtain a practicable means for keeping the strip in position, the following construction is preferably adopted. The strip—say at two points in its length—is provided with a lug, b', which is narrowed at b'. The follower is chambered out in its side to receive the lug, and the chamber c', opposite the lower larger portion of the lug, is extended into the follower to receive a spring, D, whose function is to exert an elastic pressure outwardly against the lug, and thereby cause the strip B to slip whenever the relative position of the follower and the box shall permit of it upon the follower, and thereby keep its edge b against the side a, and, on the other hand, to yield when the follower moves in the opposite direction, and allow the strip to be slipped inwardly upon the follower. At the same time the lug serves to steady the strip in place upon the follower. The strip is notched along its edge b to provide openings for the oil, and the side a of the box is for a similar purpose made a separate piece and with channels a' behind it. A further important feature of the strip is shaping it to form or providing it with the lip b' at its upper outer edge. This lip serves to round the package at its lower side corner, and to insure any part of the bag from getting into the joint between the follower and the side of the box. There may be a corner-strip, E, at the upper corners of the box to round the package at its upper corners.

We claim—

1. An oil-expressing box whose follower is provided with a strip to close the joint between the follower and the sides of the box.
2. An oil-expressing box whose follower is provided with a strip to close the joint between the follower and the side of the box, said strip being laterally adjustable upon the follower, for the purpose described.
3. In combination with the box A and the follower C, the strip B, having the lip b^2 , substantially as described.
4. The combination of the follower C, chambered at c' , with the strip B, having the lug b' , and the spring D, substantially as described. 15
